UNITED STATES PATENT OFFICE.

CHARLES W. ELLIS, OF INDIANAPOLIS, INDIANA.

PACKER.

SPECIFICATION forming part of Letters Patent No. 717,826, dated January 6, 1903.

Application filed May 31, 1902. Serial No. 109,766. (No model.)

To all whom it may concern:

Be it known that I, CHARLES W. ELLIS, a citizen of the United States, residing at Indianapolis, in the county of Marion and State 5 of Indiana, have invented certain new and useful Improvements in Packers, of which the following is a specification.

My invention consists in certain improvements in packers, and has for its object a 10 means for packing all kinds of fluffy homogeneous material, such as bran, flakes, &c.

The object consists, further, in providing a packer having a movable platform which carries a plate mounted in ways to which the 15 casing which incloses the sack is secured, a cylinder through which the material is fed into the sack, a reciprocating plunger working within said cylinder, and a chute connecting with the cylinder through which the 20 material is fed, the said chute being provided with a valve which is operated by a crank-arm secured to the shaft to which the valve is secured, the said crank-arm having an upright pivotally secured thereto, which is 25 formed into a hook on the upper end and which hook engages with an arm on the plunger-beam, and through which construction an alternating movement is imparted to the valve, thus discharging the material to be 30 packed into the cylinder in an alternating manner.

There are other features, and the construction and arrangement of the several parts will be hereinafter more particularly 35 described, and then pointed out in the claims.

Referring to the accompanying drawings, which are made a part hereof and on which similar numerals of reference indicate similar parts, Figure 1 is a front elevation of my 40 packer and shows the movable platform in its lowest position. Fig. 2 is a side elevation of the construction shown in Fig. 1. Fig. 3 is a central vertical section of the packer, on a considerably-enlarged scale, and shows 45 the platform raised and enveloping the cylinder, in this figure the uppermost or driving mechanism of the packer being broken away. Fig. 4 is a side elevation of the lower portion of the packer with the platform 50 raised and also showing the manner in which the movable platform actuates the mechanism for operating the valve in the chute.

Fig. 5 is a horizontal sectional view of the packer and shows the platform in plan view. This figure also shows how the casing is ad- 55 justably secured to said platform. Fig. 6 is a fragmentary detail, on an enlarged scale, of the vise-shaped clutch mechanism which regulates the downward movement of the platform, as well as determining the pressure 60 on the material by the plunger; and Fig. 7 is a fragmentary detail in elevation of the platform and shows the manner of inserting the adjustable block that forms the base when packing material into barrels. 65

In the drawings, 1 represents the uprights of the framework of the packer which forms the guide for the platform.

2 is the movable platform. The platform 2 is provided at each end with a standard 3, 70 which stands vertically with and against the uprights 1 of the frame. The standards 3 are provided with the yokes 4, which extend across the face of the uprights 1 and keep the two parts in alinement. The yokes also form 75 a bearing for the vertical rods 5, which are secured to the platform 2 at the bottom and have an eye at the top, to which the chains 6 are secured. The chains 6 extend upward and engage with the grooved wheels 7 by means 80 of the lugs 8 and hooks 9.

The packer is provided at each side with one of the grooved wheels 7, which are mounted on the transverse shaft 10, suitably secured in bearings in the framework of the 85 packer. On each side of the packer and mounted on the transverse shaft 10 and adjacent to the grooved wheels 7 are the balance-wheels 11, having a grooved periphery, which form a seat for the cables 12. Each of the 90 wheels 11 has a cable 12 secured thereto, each of which has a balance-weight 13 secured to the suspended end. The balance-wheels 11 are each provided with a friction-clutch which regulates the downward move- 95 ment of the platform, and on the release of the said clutches, which will be hereinafter described, and under the tension of the weights 13, as previously described, the platform 2 is raised. The movement of the plat- 100 form also regulates the amount of compression exerted by the plunger on the material being packed. Each friction-clutch is formed like a vice composed of the jaws 14

and 15, between which the wheels pass. The jaws 14 and 15 of the clutches are mounted on the threaded stud-shafts 16, each of which is secured to a suitable base fixed to the framework of the packer. A coil-spring 17 encircles each of the shafts 16 between the jaws of the clutches. The springs have a tendency to relax the pressure of the jaws on the wheels 11 when the lower ends of the jaws are actuated. The shafts 16 are provided with the hand-wheels 18 and 19, one of which regulates the longitudinal movement of the jaws, while the other acts as a jam-nut. The lower ends of the jaws 14 are provided with grooved friction-wheels 20, while the jaws 15 carry the cams 21, which engage with said friction-wheels. The cams 21 are mounted on the shafts 22, which extend to the rear of the framework 1. The shafts 22 have the crank-arms 23 secured to the rear ends thereof and which are connected together by the connecting-rod 24. One of the shafts 22 extends forward and has the crank-arm or hand-lever 25 secured thereto, so that on actuating the hand-lever 25 the shafts 22 and clutches are operated simultaneously through the connecting-rod 24. When the wheels 11 are released from the clutches, the weights 13 cause the platform to rise. To limit the upward movement of the platform, I secure the stops 28, having a flexible cushion, to the side of the uprights 1 of the framework of the packer. When the platform rises, it envelops the vertical cylinder 27, which is secured at its upper end in the frame 1. The platform rises until the floor thereof is approximately twelve inches from the lower end of the cylinder 27, which provides ample room for the first discharge of the material, and hence no descent of the platform takes place on the first compression. The upper end of the cylinder 27 is closed. A plunger-beam 29 passes through the cover of the cylinder and has the plunger-head 30 secured thereto, which compresses the material. The upper end of the plunger-beam 29 has the guide-strips 31 secured thereto, which strips engage with the fixed guide 32, which guide prevents any lateral movement of the upper end of said beam. A pitman 33 is pivotally secured to the beam 29, which pitman is secured to the crank-arm 34 on the shaft 35, and through the shaft 35, gear-wheels 36 37, and the pulley 38 the plunger-beam 29 is operated.

A chute 39 connects with the cylinder 27, through which the material is fed. The chute 39 is provided with a valve 40, mounted on the transverse shaft 41. The shaft 41 has a crank-arm 42 secured to each end. The arm 42 on one end of the shaft carries the weight 43, (see Fig. 1,) which insures the closing of the valve. The valve 40 is actuated by connecting the upright 44 to one of the crank-arms 42. The upright 44 has a hook 45 formed on the upper end thereof, which stands in the path of and engages with an arm 46, secured to

the plunger-beam 29. The arm 46 on the plunger-beam comes into contact with the hook 45 on each upward stroke of the plunger, which contact opens the valve 40 in the chute. The upright 44 is made in two parts and can be adjusted so that the hook will engage with the arm 46 at a desired point, and thus determines not only the throw of the valve 40, but regulates the amount of the discharge. It will be readily seen that through this construction I can procure a discharge of various amounts, which is one of the main features of this invention. I may also state that the contact of the arm 46 on the plunger-beam and the hook 45 is near the terminus of the upward stroke of the plunger-beam, the valve 40 opening when the plunger-beam is above the egress of the chute 39.

The upright 44 passes through a horizontal sliding plate 48, which plate is mounted in ways cut in the sides of the box or trough construction 47, which is fixed. (See Fig. 4.) The sliding plate 48 when actuated, and which will be hereinafter described, moves the upright 44 into or out of the path of the arm 46 on the plunger-beam. The upright 44 normally stands in the path of the arm 46 under the tension of the spring 49 during the time the valve 40 is being operated, and only when the upright 44 is thrown out of contact with the arm 46 is the valve 40 at rest, the reason for which will be hereinafter fully described.

It will be seen by examining Figs. 2 and 4 of the drawings that an upright 50 extends from the lower end of the packer near the floor up to a point immediately above the box 47, where it terminates. This upright 50 passes through the sliding plate 48 in the same manner as the upright 44. The upright 50 is pivotally connected to the framework of the packer at the pivotal bearing 51. The upright 50 is provided with two cams or inclines 52 and 53. The cam 53 is made integral with the upright, while the cam 52 is secured in an adjustable manner by the overlapping plate 55, carrying the slots 54, through which the bolts 55 pass. The upright 50 is actuated by the cams 52 and 53 coming in contact with ears secured on the movable platform 2 and standard 3. When the platform ascends or descends, the ears thereon actuate the upright 50, and through the sliding plate 48 the upright 44 is either thrown into or out of contact with the arm 46, secured to the plunger-beam. Thus it will be seen that the platform actuates the upright 50 automatically, which in turn moves the upright 44 into engagement with the arm 46 on the plunger-beam and through which construction a reciprocating movement is imparted to the upright 44, and through the crank-arm 45, which is pivotally secured to the lower end of the upright 44 and the valve-shaft 41, the valve 40 in the chute 39 is oscillated.

One of the standards 3 of the movable platform 2 is provided with an ear 56, rigidly secured thereto, and which engages with the

cam 53 on the upright 50 on the ascent of the platform and moves the upright from the dotted lines in Fig. 4 to the position occupied by said upright in full lines. This moves the 5 upper end of the upright 50 backward, and through the sliding plate 48 the upright 44, which is pivoted below the plate 48, is moved until the hook 45 on the upper end stands in the path and is actuated by the arm 46 on the 10 plunger-beam 29. The platform 2 is provided with a second ear 57, which comes into contact with the cam 52 on the lower end of the upright 50 and which contact moves the upright in the opposite direction from the 15 previous operation, which also moves the upright 44 out of contact with the arm 46. This last operation takes place when the platform has reached the end of the downward movement, at which time the valve 40 is at rest 20 and no material being discharged. When the platform has reached the bottom, the sack in which the packing has taken place is filled and not until the full sack is removed and replaced by an empty one and the platform 25 has risen to the terminus of its upward movement, at which time the ear 56 on the standard 3 comes into contact with the cam 53, when the valve 40 is again thrown into operation. It will be noted, however, that I in 30 no wise interfere with the operation of the plunger, which in my packer is constantly in motion. Pivoting the upright 50 between the cams 52 and 53 provides a means for actuating said upright in both directions, as has 35 been previously described.

In Fig. 5 of the drawings I have shown the casing 26 secured to a sliding plate 58, which plate slides in the ways 59, secured to the platform 2. This construction provides a 40 means for removing said casing and replacing the same by casings of various sizes or by substituting a block that forms a base when I desire to pack into barrels. (See Fig. 7.)

Having thus fully described my said invention, what I desire to secure by Letters Patent is—

1. In a packing-machine, a platform mov- 45 ably mounted in the framework of the packer, uprights forming a guide for the platform, a plate on the platform, a casing secured to the plate, means removably securing the plate to the platform, a cylinder mounted in the framework of the packer, a plunger-beam 50 suitably mounted in the framework and working within the cylinder, a chute connecting with the cylinder, as and for the purposes set forth.

2. In a packing-machine, a platform mov- 55 ably mounted in the framework of the packer, uprights forming a guide for the platform, a cylinder mounted in the framework, a chute connecting with the cylinder, a plunger-beam adjustably secured in the framework of the 60 packer and working within the cylinder, an upright adjustably secured to the framework, 65 cams on the upright, cams on the platform

which contact the cams on the upright, a plate movably mounted engaging with the upright, an upright 44 passing through the 70 movable plate, a hook on said upright, an arm secured to the plunger-beam which contacts said hook on the upright 44, a crank-arm connecting with the upright 44, a valve-shaft passing through the chute and connect- 75 ing with the crank-arm, a valve mounted on the shaft and working within the chute, as and for the purposes set forth.

3. In a packing-machine, a platform mov- 80 ably mounted in the framework of the packer, uprights forming a guide for the platform, a cylinder rigidly secured in the framework, a chute connecting with the cylinder, a plunger-beam adjustably secured in the frame- 85 work of the packer and working within the cylinder substantially as shown, means for operating said plunger-beam, an arm rigidly secured to and moving with the plunger-beam, an upright suitably mounted and having the upper end formed in a hook which engages 90 with the arm on the plunger-beam, an up- 95 right composed of sections adjustably secured together, a spring secured to the upright and the framework of the packer, a crank-arm connecting with the adjustable upright, a shaft secured to the crank-arm, the said shaft passing through the chute, a valve rigidly se- 100 cured to and moving with said shaft, the adjustable upright providing a means for regulating the length of the sweep of the valve.

4. In a packing-machine, in combination with the main frame, a platform movably mounted between the framework of the packer, a cylinder mounted therein, a chute connecting with the cylinder, a shaft mounted in the chute, a valve secured to the shaft, crank-arms secured to the valve-shaft, a weight secured to one of the arms, an upright 105 pivotally secured to one of the arms which passes through the sliding plate, the said up- 110 right composed of sections secured together by slots and bolts which provides a means for adjusting said upright, a hook on the up- 115 right, a plunger-beam adjustably mounted in the framework of the packer, the lower end of the beam working in the cylinder, an arm rigidly secured to the plunger-beam 120 which engages with the hook on the upright and provides a means for actuating the valve in the chute.

5. In a packing-machine, a cylinder mount- 125 ed in the framework of the packer, a plunger-beam suitably mounted in the framework and working within the cylinder, a chute connect- 130 ing with the cylinder, an upright pivot- ally secured to the framework of the packer, cams on said upright, a movable platform mounted in the framework of the packer, up- 135 rights of the framework which form a guide for the platform, means on the platform which engage with the cams on the upright, a slid- 140 ing plate movably mounted in a stationary trough, a stationary trough which supports the sliding plate, a slot in the plate which en-

- gages with the main upright, a secondary slot in the plate, a secondary upright engaging with the secondary slot in the plate, a crank-arm pivotally secured to the secondary upright, a shaft secured to the crank-arm, a valve secured to the shaft, a hook on the secondary upright, means for engaging with the hook for operating the upright, as and for the purposes set forth.
10. 6. In a packing-machine, a cylinder mounted in the framework of the packer, a chute connecting with the cylinder, a plunger-beam movably secured in the framework of the packer one end of which works within the cylinder, guide-strips secured to the plunger-beam, a stationary guide engaging with the strips on the plunger-beam, a pitman secured to the plunger-beam, a crank-arm secured to the pitman, a shaft secured to the crank-arm, 15 an arm 46 rigidly secured to the plunger-beam and moving therewith, an upright 44 carrying a hook thereon, means for engaging said hook for operating the upright, a crank-arm pivotally connected with the upright, a shaft 20 secured to the crank-arm, a valve secured to the shaft and working within the chute.

7. In a packing-machine, a movable platform mounted between the uprights of the framework of the packer, standards secured to the platform which rest against the uprights of the frame, stops secured to the uprights which limit the upward movement of the platform, cushions on the stops, yokes rigidly secured to the standards the ends of which extend across the face of the uprights, 30 apertures in the yokes, rods passing through the apertures, chains secured to the rods, grooved wheels secured to the chains by means of the lugs and hooks, a transverse shaft suitably mounted in the framework which engages with the grooved wheels, balance-wheels secured to the transverse shaft, cables secured to the balance-wheels, weights secured to the cables, as and for the purposes set forth.

In witness whereof I have hereunto set my 45 hand and seal, at Indianapolis, Indiana, this 12th day of May, A. D. 1902.

CHARLES W. ELLIS. [L. S.]
